UNITED STATES PATENT OFFICE.

WILLIAM S. AUCHINCLOSS, OF NEW YORK, N. Y.

IMPROVEMENT IN APPARATUS FOR INDICATING THE POSITION OF ELEVATORS.

Specification forming part of Letters Patent No. 104,535, dated June 21, 1870.

To all whom it may concern:

Be it known that I, WILLIAM STUART AUCHINCLOSS, of the city, county, and State of New York, have invented a new and Improved Elevator-Indicator; and I do hereby declare the following to be a full, clear, and exact description thereof, which will enable those skilled in the art to make and use the same, reference being had to the accompanying drawing, forming part of this specification.

The drawing represents a sectional front view of this invention.

This invention consists in the arrangement of an indicator-rod extending through the several stories of a building, and provided with or connected to suitable indices working over scales secured one in each story, in combination with the car or platform of an elevator in such a manner that the position of said car or platform can be observed at all times and in every story, and also, if desired, the direction in which the car or platform moves.

In the drawing, the letter A designates the elevator-well in which the car or platform B moves. This car or platform connects with the indicator-rod C in such a manner that when the car or platform travels from the top of the well to its bottom the rod C descends ten or twelve inches or any small distance, and vice versa.

It is obvious that the object of reducing the motion of the indicator-rod can be effected by various means. In the drawing I have shown a rope, a, which extends from the car over a large pulley, b, and from the shaft of this pulley extends a rope, c, to the indicator-rod, and if the extreme motion of the car is forty feet and it is desired to reduce the motion of the indicator-rod to one foot the diameter of the pulley b must be forty times as large as that of its shaft, or of that portion of its shaft to which the rope c is connected. The mechanism for reducing the motion may, however, consist of racks and pinions, screws and nut, levers, or a worm and screw, or of any other suitable combination of devices which will produce the desired result.

The indicator-rod extends down through the various stories of the building in any convenient place, and it carries a series of indices, d, of any convenient form or shape, which travel over scales e, marked with lines 1, 2, 3, 4, &c., to indicate the various stories of the building. When the car rises in the well the indicator-rod rises also, and whenever the car stops the indices on the indicator-rod point to the story where the car has stopped, so that the position of the car and the direction in which it moves can be observed at all times. The connection between the car and the indicator-rod might, however, be also so arranged that the latter would receive an intermittent motion, carrying the indices from one mark on the scales to the other; but in this case the direction in which the car moves could not be observed with the same convenience as it can by the arrangement previously described.

The scales e may be made in a variety of forms—either flat, as shown, or in the form of sleeves surrounding the indicator-rod, or in the form of dials with indices connected to the rod, so as to receive a revolving motion. The position of the scales and of the indicator-rod will of course be selected as convenience may dictate.

It is self-evident that for the rod C a cord or chain might be substituted without changing the result.

What I claim as new, and desire to secure by Letters Patent, is—

The indicator rod or cord C, carrying or operating one or more indices, d, in combination with the car or platform B of an elevator, substantially in the manner and for the purpose herein shown and described.

This specification signed by me this 2d day of May, 1870.

WM. S. AUCHINCLOSS.
